UNITED STATES PATENT OFFICE

EDWIN E. ARNOLD, OF PITTSBURGH, PENNSYLVANIA, ASSIGNOR TO WESTINGHOUSE ELECTRIC & MANUFACTURING COMPANY, A CORPORATION OF PENNSYLVANIA

MULTICAR DOOR OPERATOR

Application filed December 27, 1930. Serial No. 505,063.

My invention relates to elevator door-operating systems and more particularly to hatchway-door apparatus for plural-elevator systems, in which two or more cars are operated independently of each other in the same shaft.

The object of my invention, in general, is to provide simple, inexpensive and easily operated mechanism for opening the hatchway doors at the floor landings in a plural elevator system when the cars stop at the landings, and for closing the doors when the cars complete their stops.

A more specific object of my invention is to provide an elevator-door system for a plural elevator in which relatively small electric motors may be employed for operating the system of hatchway doors, and in which only one hatchway-door-operating motor will be required for each car.

Another object of my invention is to provide a door-operating system in which no door-operating apparatus need be carried on the car.

A further object is to provide a hatchway-door-operating system for a plural elevator in which the stopping of any one of the cars at a floor landing will cause the hatchway door at that landing to open.

It is also an object of my invention to provide a door-operating mechanism that will occupy a minimum amount of hatchway space.

Other objects of my invention will, in part, be obvious and will, in part, appear hereinafter.

For an illustration of one of the various embodiments of my invention, reference may be had to the accompanying drawings, in which;

Figure 1 is a diagrammatic representation of an elevator hatchway including means embodying my invention.

Fig. 2 is a diagrammatic representation of the hatchway shown in Fig. 1, provided with

two elevator cars, viewed at a right angle to that of Fig. 1;

Fig. 3 is an enlarged view, in side elevation of the operating mechanism connected to each hatchway door;

Fig. 4 is an enlarged view, in side elevation, as viewed from the interior of the hatchway, of the hatchway-door-operating mechanism shown in Fig. 3.

Fig. 5 is an enlarged plan view of one of the electromagnetic clutches employed in the door-operating mechanism shown in Fig. 1, part of the cover being broken away to disclose a pair of interlocking switches that are associated with the elevator system.

Fig. 6 is a view, in side elevation, of the clutch and switch shown in Fig. 5, and

Fig. 7 is a diagrammatic representation of an electrical circuit for controlling the door-operating mechanism shown in the preceding figures.

Referring more particularly to the drawings, I have illustrated therein an elevator hatchway structure 10 in which are disposed two elevator cars A and B. Although the hatchways of plural elevators are usually constructed for serving many floors in very tall buildings, and, obviously, may contain more than two cars, the one illustrated in the drawings is, for the sake of simplicity, shown as serving only five floors, 1, 2, 3, 4 and 5. The cars A and B may be suspended by a plurality of cables Ca and Ca', for independent operation in the hatchway in any suitable manner, such, for instance, as that disclosed in the copending application of Henry D. James, Serial No. 255,049, filed February 17, 1928, and assigned to the Westinghouse Electric & Mfg. Company. A pent-house 13 for the machinery of car A, and a pent-house 14 for the machinery of car B are disposed at the top of the elevator hatchway 10.

The entrance from each floor landing to the cars in the hatchway is provided with a two-panel door 16; the doors for the first,

second, third and fourth floors being shown in closed position and the door for the fifth-floor landing is shown in its open position.

In order that the hatchway door at a landing may be opened when the car 16 stops at that landing, a door motor 17, provided with a driving drum 18 is located in the pent-house 14. Wound around the driving drum 18, to be driven thereby through frictional engagement, therewith, is a door-operating cable 19 which extends downwardly past the hatchway doors. A weight 20 is secured to the lower end of the cable 19 and disposed in a guideway 21 at the bottom of the hatchway.

15 The upper end of the cable passes over a pulley 22, on the ceiling of the pent-house 14, to a weight 23 disposed in a guideway 24 on the side wall of the pent-house. The weights 20 and 23 keep the cable 19 under tension and maintain it in good frictional contact with the driving drum 18, so that operation of the driving drum will raise or lower the cable in the hatchway, depending upon the direction of rotation of the door motor.

25 In order that the hatchway doors may be coupled to the cable 19 for operation thereby, a sleeve 26 (Figs. 3 and 4), provided with a projection or pin 27, is mounted upon the cable at a point near each hatchway door. 30 Connecting members are provided for each door and inasmuch as they are all the same, only those for one door will be described in detail. The sleeve 26 is firmly secured to the cable 19 by means of a pair of clamps 28, 35 which are removably bolted to the cable in order that the position of the sleeve on the cable may be changed when desired.

The pin 27 extends through the central portion of the sleeve 26 and is provided with a vertically disposed hole of sufficient size to permit the threading of the cable therethrough when the sleeve is mounted upon the cable with the pin and the sleeve prevents the pin from turning and wearing the cable.

45 A lever 30, to be actuated by the raising or lowering of the door cable, is pivotally connected at one end thereof, to the free end of the pin 27. The other end of the cable lever 30 (Figs. 5 and 6) is welded, or otherwise firmly secured, to an actuating electromagnetic clutch member 31 that cooperates with an armature clutch member 32 to constitute an electromagnetic clutch 33. The cooperating clutch members 31 and 32 are concentrically and rotatably supported upon a pin 34 mounted in a base plate 36 which is firmly affixed to the wall of the hatchway 10. The armature member 32 is seated upon the pin 34 by means of a wearing bushing 37 in a position adjacent to the base plate 36, and is retained in that position by a flanged sleeve 38. The flanged sleeve 38 is retained in its position by a washer 39, which, in turn, is 60 retained on the pin 34 by a shoulder 40 on a

stud bolt 41 which is screwed into the outer end of the pin.

The electromagnetic clutch member 31 is slidably and rotatably seated upon the body of the flanged sleeve 38 and is retained in that position by the head of the stud bolt 41. It should be noted that the distance between the head of the stud bolt 41 and the shoulder 40 is sufficient to permit the clutch member 31 to travel into and out of engagement with its cooperating armature clutch member 32. A coil spring 42 is mounted between the clutch members in a position concentric with the pin 34 for biasing the clutch members away from each other.

70 In order to overcome the biasing effect of the spring 42 and cause the clutch members 31 and 32 to engage when the hatchway door is to be opened, an electromagnetic coil 43 is mounted upon the clutch member 31. The coil 43 may be electrically connected in some portion of the control system for the car in such manner that it will be energized when the car makes a stop at the landing at which the clutch is located, as will be hereinafter more 80 fully explained.

85 A plurality of cooperating saw-like teeth 44 and 45 are so disposed upon the cooperating faces of the clutch members that they will grip each other firmly when they are brought together by the energization of the coil 43. Preferably, the teeth 44 and 45 are inclined at such an angle that the clutch members will grip each other firmly when the clutch is energized and the cable is raised to open the door, but which will facilitate the separation of the clutch members when the coil 43 is deenergized and the cable is lowered.

95 An arm 50, to be raised by the rotation of the clutch is mounted upon the armature member 32 and firmly affixed thereto. The outer end of the arm 50 is provided with a pin 51 (Figs. 3 and 4) on which is mounted a roller 52. The roller 52 is so disposed in a slot 53 in the upper end of a vertically disposed connecting rod 54 that the rod will be raised when the arm 50 is raised. A set screw 56 is disposed in the top portion of the rod 54 to permit adjustment of the rod and the roller.

105 The lower end of the rod 54 is pivotally connected to a lug on a toggle lever 57 for operating the hatchway door 16. One end of the toggle lever 57 is pivotally supported, by a bolt 58, on a bracket 59 which is secured to the side wall of the hatchway. The other end of the lever 57 is pivotally connected to one end of a central lever 60 (Fig. 1), the other end of which is pivotally connected to one end of a lever 61. The outer end of the lever 61 is pivotally connected to the outer panel of the door 16, and the middle portion of the central lever 60 is pivotally attached to the inner door panel, so that the raising of the toggle lever 57 by the con- 115

120

125

130

necting rod 54 will break the toggle levers, 57, 60 and 61 from their straight-line position and thereby cause the door panels to move to the left into their full-open position. A hand-grip 62 is mounted upon the central toggle lever 60 by which the door may be manually opened from within the car, when desired.

While the door motor 17 and the cable 19 may be reversed to close the hatchway door after it has been opened, I provide an additional door-closing means comprising a spring operator 66, as a matter of additional safety. The operator 66 may be of any well known type comprising a cylindrical casing 67, a piston 68 disposed within the casing, a piston rod 69 firmly connected to the piston and extending upwardly through an aperture in a cap 70 on the cylindrical casing and an operating spring 71 that is coiled around the piston rod 69 and placed under compression between the piston and the cap. The lower end of the cylinder 67 is pivotally connected to a bracket 72 on the side wall of the hatchway, and the upper end of the piston rod is pivotally connected to a lug 73 on the toggle lever 57 in such manner that the spring 71 is held under compression, which is increased by the operation of the toggle levers when the door is opened, therefore, if the opening force is released, the spring will expand to cause the door to move to its closed position.

Referring now to car A, in order that the hatchway doors may be opened for that car when it makes a stop at a landing, a door motor 76, provided with a driving drum 77, is mounted in the upper pent-house 13 for operating a door-opening cable 78. The cable 78 extends past the hatchway doors and is wound around the driving drum 77 with its upper end extending over a pulley 79 to a weight disposed in a guideway 81. A weight 82 is attached to the lower end of the cable 78 to keep it under tension. The cable 78 is connected to the lug on the door toggle lever 57 by means of a lever 30a, an electromagnetic clutch 33a, an arm 50a, and a connecting rod 83, in the same manner as the cable 19 and operates in the same way.

A pair of switches 84 and 85 are mounted upon each electromagnetic clutch (see Figs. 5 and 6) for electrically interlocking the clutch and arm with the control system of the car (not shown).

The switch 84 is disposed to engage a contact member 84a on the clutch 32 and is so biased toward an open position by a spring 84b that it will open when the clutch member 31 moves inwardly upon being energized. The switch 85 is also disposed to engage a flanged portion of the contact member 84a when the arm is in its lower or inactive position. The switches may be connected in series in a portion of the control system represented

by the conductors bearing the legend "to control circuit", so that, if the clutch is energized or the arm is raised, the control circuit for the car will be broken, and the car cannot operate.

In order to permit the operation of one door-opening cable by one car when the other cable is inactive without opening the switches 84 and 85 associated with that other cable, the slot 53 in each of the connecting rods 54 and 83 is extended downwardly a sufficient distance below the roller to permit the rod to be removed upwardly without causing any movement of the roller. Hence, with this lost-motion connection, if either one of the connecting rods is raised to operate the door, the other rod, connected to the same toggle lever, will also be raised, but the slotted portion of the rod will slide along the roller therein without moving it. Hence, it will not disturb the door-operating arm or clutch at that door for the other car.

The door-operating apparatus so far described may be coupled to the car-control system in any suitable manner, such that, when one of the cars makes a stop at a floor landing, the clutch corresponding to that car at that landing will be automatically energized and then the door motor will be automatically energized to raise the door cable and thereby open the hatchway door. When the car is conditioned to leave, the motor and clutch will be deenergized, and the door will return to its closed position, under the action of the spring operator 66.

In Fig. 7, I have illustrated one manner in which the door operating apparatus may be coupled to a power control system. In this figure, the door-operating apparatus for car A is shown as controlled by a relay AR which is disposed to be energized when the car A is conditioned to run and to be deenergized when the car is conditioned to stop.

The operation of the relay AR supplies energy to the door-operating apparatus which is controlled by means of a floor selector AS in such manner that the clutch member corresponding to the floor at which the car is to stop will be energized and then the car motor 76 will be energized to open the hatchway door at that landing.

The floor selector AS may be located at any suitable point, for example, in the pent-house or in the elevator shaft. The selector is similar to those usually employed in elevator signalling systems and is provided with a set of "up" contact segments and a set of "down" contact segments which are disposed to be engaged by brushes 85 and 86 which are mounted upon, and insulated from, a movable arm MA.

The movable arm MA is operated by a screw S which may be driven by some operating mechanism connected to the car. The frictional engagement between the arm MA

and the operating screw S causes the arm to bear upon the "up" contact segments when the car is travelling upward and upon the "down" contact segments when the car is travelling downward. The contact strips 87 and 88 are connected for energization by the closing of the contact members *b* on the relay AR when that relay is deenergized. The contact segments, one for each floor, lying adjacent to the contact strips are connected to the coils of the clutches disposed at the hatchway doors for selectively energizing such clutches when the car makes a stop.

The outer rows of contact members are provided for energizing the motor 76 to drive the drum 77. It will be noted that the contact segments for the clutches are longer than the contact segments for the motor. The difference in length causes the clutches to be energized before the motors to thereby insure correct operation of the system.

Although any suitable motor may be employed, I prefer a three-phase torque motor. A brake 89 is mounted on the shaft of the motor 76 to prevent rotation of the drum 77 when the motor is deenergized.

A controller 90 is mounted upon one end of the motor shaft and is provided with contact segments and brushes that act as limit switches to deenergize the motor after it has completed its rotation in either direction.

A pair of reversing switches 91 and 92 controlled by the floor selector, are provided for reversing the direction of rotation of the motor 76.

The door-operating apparatus for car B is provided with a control system similar to that described for car A, comprising a control relay BR, a floor selector BS, a pair of reversing switches 93 and 94 for the motor 17, a brake 95 for the driving drum 18, and a controller 96 for operating the limit switches to stop the motor when it completes its movement.

The invention may be better understood from an assumed operation thereof. Assuming that the car B is ascending the hatchway and that the attendant thereon conditions the car to stop at third floor, then the control relay BR will be deenergized and close its contact members *b*. The closing of the contact members *b* of the relay BR supplies energy to the contact strips 100 and 101 on the floor selector BS. Inasmuch as car B is travelling upward, the contact brush 102 on the floor selector BS is in engagement with the contact strip 100 and the cooperating contact segments on its "up" side. As the car approaches the third floor, a circuit is completed for energizing the clutch 103 at the third floor, which circuit extends from conductor L₁, through conductor 104, the contact members *b* of relay BR, conductor 105, contact strip 100, brush 102, contact segment 106, conductor 107, the coil of clutch 103 and

conductor 108 to supply conductor L₂. The energization of the clutch coil causes the clutch member 31 to lock into engagement with the clutch member 32.

As the car continues its approach to the third floor, the contact brush 102 engages the contact segment 111 and thereby completes a circuit for energizing the direction relay 93 to effect the opening of the door 112, which circuit extends from supply conductor L₁, through conductor 104, the contact members of *b* relay BR, conductor 105, contact strip 100, brush 102, contact segment 111, conductors 113 and 114, feed ring 115, limit switch 116, conductor 117, the coil of relay 93 and conductor 118, to supply conductor L₂.

The energization of the relay 93 closes its contact members *a* and *b* and thereby completes a circuit for connecting the door motor 17 to a suitable source of alternating current represented by the supply conductors I, II and III to rotate that motor in a clockwise direction. The closing of the circuit for the motor also energizes the brake coil 120 and releases the brake 95. Thereupon, the drum 18 is rotated in a clockwise direction to raise the cable 19. The raising of the cable 19 lifts the cable lever 121 at the third floor and thereby rotates the member 31 of the clutch 103. Inasmuch as the clutch member 31 has been locked in engagement with the clutch member 32 by the energization of the coil of the clutch 103, the rotation of the clutch member 31 effects the rotation of the clutch member 32. The rotation of the clutch member 32 raises the clutch arm 50 which, being coupled to the connecting rod 54, causes the toggle lever 57 to be raised. The upward movement of the toggle lever 57 breaks the toggle levers 57, 60 and 61 at the third floor door from their straightline position and thereby moves the door panels to their full-open position.

As the door panels reach their full-open position, the rotation of the controller 96 by the door motor causes the limit switch 116 to open, thereby deenergizing the motor 17 and the brake coil 120, which causes the drum 18 to stop in its "door open" position. By reason of application of the brake 95 when its coil 120 is deenergized, the door will remain open until the car is conditioned to start.

Assuming now that the attendant on car B conditions the car to continue its upward trip, then the relay BR will be energized to open its contact members *b* and close its contact members *a* to effect the closing of the door at the third floor landing.

The closing of the contact member *a* on the relay BR completes a circuit for energizing the direction switch 94 to reverse the motor 17, which circuit extends from supply conductor L₁, through conductor 121, the contact member *a* of relay BR, conductor 122 feed ring 123, the contact mem-

bers of limit switch 124, conductor 125, the coil of direction switch 94, and conductor 118, to supply conductor L_2 . The energization of the direction switch 94 closes its contact members *a* and *b* for supplying alternating-current energy in a reverse direction to the motor 17 and for energizing the brake coil 120 to release the brake 95. Thereupon, the motor 17 rotates in a counter-clockwise direction to cause the winding drum 18 to lower the door cable 19 and, through it, to reverse the movement of cable arm 121 the clutch 103, the clutch arm 50, the connecting rod 54 and the toggle arms 57, 60 and 61. This operation causes the toggle arms to move into their straight-line position to close the door 112 at the third-floor landing.

However, it will be noted that, as an additional safeguard, the opening of the contact member *b* on the relay BR opens the circuit for the coil of the clutch 103 and deenergizes that clutch so that the clutch members 31 and 32 therein separate from each under the biasing effect of the spring 42. Furthermore, inasmuch as the spring operator 66 is connected to the door toggle lever 57, it will, as soon as the clutch is deenergized exert a closing effect upon the hatchway door by the force stored up in the operator spring 71.

Assuming now that car B has started down and that car A has also been conditioned to start down. As the car A is conditioned to descend, the relay AR is energized to open its contact member *b* and close its contact member *a* to effect the closing of the hatchway door at the fifth-floor landing. Inasmuch as the arms MA of the floor selector AS will not reverse their position until the car actually starts downwardly after the doors are closed, the contact brush 85 will remain on contact strip 87 and associated contact member until the door closes.

The opening of the contact member *b* of the relay AR deenergizes the coil of the clutch 126 at the fifth-floor landing. At the same time, the closing of the contact member *a* on the relay AR completes a circuit for energizing the direction switch 92 to rotate the motor 76 in a clockwise direction, which circuit extends from supply conductor L_1 , through conductor 127, the contact member *a* of relay AR, conductor 128, feed ring 129, the limit switch 130 on controller 90, conductor 131, the coil of switch 92 and conductor 132 to the supply conductor L_2 .

The energization of the direction switch 92 closes its contact members *a* and *b* and thereby completes a circuit, from the alternating current supply conductors I, II and III for energizing the motor 76 to cause it to rotate in a clockwise direction. The supply of energy from the motor 76 also energizes and releases the brake 89. Thereupon, the drum 77 rotates in a clockwise direction

and lowers the cable 78, which, in turn, lowers the cable lever 30a at the fifth floor. If the clutch has not yet been deenergized the downward operation of the lever 30a will actuate the clutch arm 50a, the connecting rod 83 and the toggle levers 57, 60 and 61 to close the door at the fifth floor. At the same time, the door closer 66, connected to the door toggle lever at the fifth floor, exerts its stored-up energy to move the hatchway door to its closed position.

As soon as the hatchway door is fully closed, the car will start downwardly, and the contact brush 86 on the arm MA of the floor selector AS will swing into engagement with the "down" contact strip 88 and the contact segments associated therewith.

Assuming now that the attendant on car A conditions the car to stop at the third floor, as it approaches that floor, then the relay AR will be deenergized to open its contact members *a* and close its contact members *b*.

The closing of the contact members *b* of the relay AR energizes the contact strip 88 on the floor selector AS and, as the car A approaches the third floor landing, the brush 86 engages the contact segment 135, thereby completing a circuit for energizing the direction switch 91, which circuit extends from supply conductor L_1 , through conductor 136, the contact members *b* of relay AR, conductor 137, contact strip 88, brush 86 contact segment 135, conductors 138 and 139, the coil of the clutch 140 at the third floor landing and conductor 108, to supply conductor L_2 .

The energization of the coil of clutch 140 at the third-floor landing causes the member 31 of that clutch to move into engagement with the cooperating member 32 so that the door 112 will be opened when the cable 78 is operated.

As the car A continues its approach to the third-floor landing, the brush 86 engages the contact segment 141 and thereby completes a circuit for energizing the direction switch 91 to effect the opening of the door 112, which circuit extends from supply conductor L_1 , through conductor 136, the contact members *b* of relay AR, conductor 137, contact strip 88, brush 86, contact segment 141, conductors 142 and 143 feed ring 144, limit switch 145 conductor 146, the coil of direction switch 91 and conductors 147 and 132, to supply conductor L_2 .

The closing of the contact members *a* and *b* of the relay 91 connects the door motor 76 to the alternating-current supply conductors I, II and III, which causes the motor to rotate in a counter clockwise direction and also releases the brake 89.

The rotation of the motor 76 raises the cable 78 which, in turn, raises the cable arm 148 at the third-floor landing. Inasmuch as the clutch 140 at the third floor landing

is energized, the raising of the cable arm rotates the clutch and thereby raises the clutch arm 50a at that landing, which, in turn, raises the connecting rod 83 and the toggle lever 57. The operation of the toggle lever 57 moves the toggle levers 60 and 61 out of their straight-line position and thereby effects the opening of the door 112. As the door moves into its full-open position, the rotation of the motor 76 causes the limit switch 145 to open, thereby deenergizing the motor and setting the brake 89 to stop the downward movement of the cable 78.

The connecting rod 83, being attached to the lever 57, also moves upwardly when the connecting rod 54 moves upwardly, but, inasmuch as the slot 53 in the upper portion of the connecting rod 83 extends downwardly for some distance, the connecting rod 83 slides past the roller on the clutch arm 50a without moving that arm. Therefore, it does not disturb the door-operating arm or the clutch car A and, hence, does not prevent car A from operating.

Therefore, it will be seen that I have provided a door-operating system by means of which the hatchway doors in an elevator shaft in which two or more cars are operated may be opened or closed by either car when they stop at a landing, and that the arrival and departure of either car, when making a stop at a landing, will cause the hatchway doors at that landing to automatically open and close for the stop.

Although I have illustrated and described only one specific embodiment of my invention, I realize that many modifications thereof may be made. Therefore, I do not desire to be limited to the precise construction illustrated and described.

I claim as my invention:

1. In an elevator system, the combination with a plurality of cars operable past a plurality of doors in a hatchway, individual means for moving said cars, and individual means for controlling said moving means to start and to stop said cars, of means for operating the doors comprising an individual door-operating motor for each car, an individual movable member for each car disposed to be operated past said doors by the motor for that car, an individual electromagnet for each of said cars disposed at each of said doors, and means operably responsive to operation of the controlling means of any one of said cars to stop that car at a landing and for energizing the electromagnet associated with that car at that landing and for energizing the motor associated with that car for moving the door at that landing to its open position.

2. In an elevator system, the combination with a plurality of cars operable past a plurality of doors in a hatchway, individual means for moving said cars, individual means

for controlling said moving means to start and to stop said cars and individual means for biasing said doors to their closed position, of means for operating the doors, comprising an individual door-operating motor for each car, an individual, movable member for each car disposed to be operated past said doors by the motor for that car, an individual electro-magnet for each of said cars disposed at each of said doors, means operably responsive to operation of the controlling means of any of said cars to stop that car at a landing for energizing the electromagnet associated with that car at that landing and for energizing the motor associated with that car for moving the door at that landing to its open position and means operably responsive to operation of the controlling means to start that car for releasing said door to its closed position.

3. In an elevator system, the combination with a plurality of cars operable past a plurality of doors in a hatchway, individual means for moving said cars, and individual means for controlling said moving means to start and to stop said cars, of means for operating the doors comprising an individual door operating motor for each car, an individual movable member for each car disposed to be operated past said doors by the motor for that car, an individual electromagnet for each of said cars at each of said doors, and means operably responsive to operation of the controlling means of any one of said cars to stop that car at a door for energizing the electromagnet associated with that car at that door for moving said door to its open position, and means operably responsive to the energization of an electro-magnet at a door for preventing operation of the car with which the electro-magnet is associated while it is deenergized.

4. In an elevator system, the combination with a plurality of cars operable past a plurality of doors in a hatchway, individual means for moving said cars, and individual means for controlling said moving means to start or to stop said cars, of means for operating the doors comprising an individual door operating motor for each car, an individual movable member for each car, to be operated past said doors by the motor for that car, an individual door operating arm for each car disposed at each door, to be operated by the movable member for that car, an individual electro-magnet for each of said cars at each of said doors for connecting the corresponding arm to the corresponding movable member and means operably responsive to operation of the controlling means of any one of said cars to stop that car at a door for energizing the electro-magnet associated with that car at that door and for energizing the corresponding motor to actuate the door operating arm to open the door, and interlocking means op-

erably responsive to an active position of an arm at a door for preventing operation of the car with which that arm is associated while it is in its active position.

5. In an elevator system, the combination with a plurality of cars operable past a plurality of doors in a hatchway, individual means for moving said cars, and individual means for controlling said moving means to start or to stop said cars, of means for operating the doors comprising an individual door operating motor for each car, an individual movable member for each car to be operated past said doors by the motor for that car, an individual door operating arm for each car disposed at each door to be operated by the movable member for that car, an individual electro-magnet for each of said cars at each of said doors for connecting the corresponding arm to the corresponding movable member and means operably responsive to operation of the controlling means of any one of said cars to stop that car at a door for energizing the electro-magnet associated with that car at that door and for energizing the corresponding motor to actuate the door operating arm to open the door, and interlocking means operably responsive to the active position of an arm at a door for preventing operation of the car with which that arm is associated, and lost-motion connecting means between said arms and said doors to permit either car to open any door at which it may stop without moving the arm associated with the other car at that door.

6. In an elevator system, the combination with a car operable past a plurality of hatchway doors disposed at different landings, means for moving said car and means for controlling said moving means to start or to stop said car, of means for operating said doors comprising a motor, a movable member disposed to be operated past said doors by said motor, an arm disposed at each door and connected thereto, a clutch disposed at each door, means operably responsive to operation of the control means to stop the car at a door for energizing said clutch to connect the arm at that door to the movable member and for energizing said motor to operate the movable member and the arm to open the door, and interlocking means operably responsive to the open position of said arm for preventing the operation of said car.

7. In an elevator system, the combination with a car operable past a plurality of hatchway doors disposed at different landings, means for moving said car and means for controlling said moving means to start or to stop said car, of means for operating said doors comprising a motor, a movable member disposed to be operated past said doors by said motor, an arm disposed at each door and connected thereto, a clutch disposed at each door, means operably responsive to op-

eration of the control means to stop the car at a door for energizing said clutch to connect the arm at that door to the movable member and for energizing said motor to operate the movable member and the arm to open the door, and interlocking means operably responsive to energization of said clutch for preventing the operation of said car while said clutch is energized.

In testimony whereof, I have hereunto subscribed my name this 23rd day of December, 1930.

EDWIN E. ARNOLD.
